UNITED STATES PATENT OFFICE.

CHARLES L. CRABB, OF MILLINGTON, NEW JERSEY, ASSIGNOR TO TOPPING BROTHERS, OF NEW YORK, N. Y., A CORPORATION OF NEW YORK.

MACHINE FOR TRANSPARENTIZING SHEETS OF PAPER OR OTHER MATERIAL.

1,037,873.

Specification of Letters Patent. Patented Sept. 10, 1912.

Application filed November 24, 1911. Serial No. 662,141.

To all whom it may concern:

Be it known that I, CHARLES L. CRABB, a citizen of the United States, and resident of Millington, in the county of Morris and State of New Jersey, have invented a new and useful Improvement in Machines for Transparentizing Sheets of Paper or other Material, of which the following is a specification.

10 The object of this invention is to provide certain improvements in a machine for transparentizing sheets of paper or other material.

15 The machine includes a bath of transparentizing liquid, a set of drying rolls, and a sheet carrier arranged to convey the sheets being treated from the bath to the drying rolls.

20 The machine may also include a set of feeding rolls for receiving the sheets at the liquid bath and feeding them onto the sheet carrier; also means for heating the liquid bath and the drying rolls; also a receptacle for receiving the treated sheets, and also a 25 delivery roll arranged to receive the sheets from the drying rolls and deliver them into the receptacle.

25 A novel arrangement of blotting sheets on the drying rolls is also provided and various 30 improvements are made in the construction, form and arrangement of the several parts of the machine whereby the treatment of the sheets is materially facilitated and the quality of the work improved.

35 A practical embodiment of my invention is represented in the accompanying drawings, in which—

Figure 1 represents the machine in top plan, the upper feed roll and the upper drying roll being partly broken away. Fig. 2 is 40 a view of the machine in side elevation. Fig. 3 is a vertical section taken in the plane of the line A—A of Fig. 1. Fig. 4 is a detail view, partly in side elevation and partly 45 in section, illustrating the geared connection between the driving crank shaft, the feed roll shafts and the tape carrier drive shaft. Fig. 5 is a detail vertical cross sectional view taken in the plane of the line 50 B—B of Fig. 2. Fig. 6 is a detail cross sectional view taken in the plane of the line C—C of Fig. 2, and Fig. 7 is an enlarged

detail section through the drying rolls and their adjacent parts.

The main frame of the machine is denoted by 1, to which frame is secured a pan having a downwardly and forwardly inclined bottom and uprising front, back and side walls.

The bottom wall of the pan is denoted by 2, the side walls by 3 and 4, the front wall by 5 and the rear wall by 6.

A transverse trough is provided in the front end of the pan, forming a reservoir for the bath liquid 7. The downward and forward inclination of the bottom 2 of the pan will direct the liquid dropped thereon back into the said trough.

Upper and lower feed rolls 8, 9, have their shafts 10, 11, rotatably mounted in suitable brackets 12, 13, secured to the uprising sides 3, 4, of the pan, in such a position that the lower feed roll 9 will be substantially immersed in the liquid bath 7. The lower roll 9 is driven from the upper 75 roll 8 through intermeshing gears 14, 15, fixed to their respective shafts adjacent to the bracket 12. The shaft 10 of the upper feed roll may be journaled in spring pressed boxes 16, 17, whereby the said roll may be 80 pressed against the lower roll with the desired amount of pressure.

The upper roll 8 is driven from a driving shaft 18 through intermeshing gears 19, 20, adjacent to the bracket 13. This shaft 18 85 is herein shown as a crank shaft rotated manually by means of a crank handle 21, the shaft being mounted in the uprising side 4 of the pan, the gear 20 being within the pan and the handle 21 being exterior 90 thereto.

A supplemental frame 22 has its base 23 resting upon a horizontal seat 24 formed in the pan, which supplemental frame may be adjusted forwardly and rearwardly and secured in such adjusted positions by bolts 95 25 passing through elongated slots 26 in the said base 23 into engagement with the said seat 24.

Upper and lower hollow drying rolls 27, 100 28, have their hollow shafts 29, 30, rotatably mounted in journal boxes 31, 32, carried by the supplemental frame 22. The upper drying roll 27 is held against the lower drying

roll with the proper pressure by providing the journal boxes 31 with uprising pins 33 on which rest the levers 34 pivoted at 35 to the supplemental frame and provided with 5 adjustable weights 36.

5 The lower drying roll 28 is driven from the shaft 18 by providing a chain and sprocket connection 37, 38, 39, between the shaft 18 and the shaft 30 exterior to the pan.

10 The upper drying roll 27 is driven from the lower drying roll 28 through intermeshing gears 40, 41.

15 A sheet carrier is provided for conveying the sheets from the set of feed rolls 8, 9, to the set of drying rolls 27, 28, which sheet carrier is herein shown as an endless tape carrier, the tapes 42 of which pass around a shaft 43 adjacent to the feed rolls 8, 9, and around a shaft 44 adjacent to the drying 20 rolls 27, 28.

25 The shaft 43 is mounted in the brackets 12, 13, and is driven from the upper feed roll 8 through intermeshing gears 45, 46. The shaft 44 is mounted in brackets 47 pivoted at 48 to the supplemental frame 22. The tension on the tapes 42 may be adjusted by means of adjusting screws 49 carried by the brackets 47 and bearing against the supplemental frame 22.

30 A delivery roll 50 has its shaft 51 mounted in suitable brackets 52 secured to the supplemental frame 22, which delivery roll is driven from the lower drying roll 28 through a train of gears 53, 54, 55.

35 A guide plate 56 is interposed between the delivery roll 50 and the set of drying rolls for guiding the sheets from the drying rolls over the delivery roll.

40 A receptacle 57 is mounted on the main frame 1 of the machine below the delivery roll 50 in position to receive the sheets therefrom.

45 Means are provided for heating the liquid bath 7 and the drying rolls 27, 28, which means is herein shown as an electrical heating apparatus of well known and approved form, a general description only of which will be herein given.

50 The wiring is denoted by 58, the main switch by 59, the rheostat by 60 and the fuse box by 61. A stationary conduit 62 is located within the liquid bath 7 at the bottom of the trough immediately beneath the lower feed roll 9 within which conduit are located 55 the heating coils 63 connected to the wiring 58. Stationary conduits 64, 65, extend through the hollow shafts 29, 30, and drying rolls 27, 28, which conduits carry the heating coils 66, 67, connected to the wiring 58.

60 These conduits 64, 65, are secured at their ends in depending arms 68 of brackets 69 secured to the top caps 70 of the supplemental frames 22.

Blotting sheets 71, 72, are wrapped around 65 the drying rolls 27, 28, the tail ends of

which blotting sheets are free so as to permit a free expansion and contraction of the blotting sheets due to varying degrees of moisture taken up from the sheets being treated, without possibility of the blotting sheets becoming wrinkled or torn. These blotting sheets are oppositely wound and fenders 73, 74, are secured to the supplemental frame 22 in position to engage the free tail ends of the blotting sheets upon opposite sides of the delivery end of the sheet carrier so as to insure the feeding in of the sheet being treated between said blotting sheets. The advance edges of these blotting sheets may or may not be secured to the drying rolls, the direction of rotation of the rolls serving to tend to wind the blotting sheets tightly thereon.

It will be seen that the leading end of the sheet carrier and the lower feeding roll are 35 both immersed in the liquid bath 7.

As the sheet to be treated is fed in between the feeding rolls and delivered thereby onto the tapes 42 of the sheet carrier, the sheet will be caused to adhere to the wet tapes 90 sufficiently to cause the tapes to convey the sheet upwardly and rearwardly into position to deliver the same to the drying rolls.

The combined action of the blotting sheets and the heat of the drying rolls, will rapidly 95 dry the sheet being treated, the sheet passing over the table 56 as it leaves the drying rolls to the delivery roll 50, which delivery roll guides the sheets into position to be dropped into the receptacle 57.

100 It is evident that various changes might be resorted to in the construction, form and arrangement of the several parts without departing from the spirit and scope of my invention; hence I do not wish to limit myself strictly to the structure herein set forth, but

105 What I claim is:—

1. In a machine of the character described, a liquid bath, a set of drying rolls, 110 a sheet carrier for conveying the sheets from the bath to the drying rolls and means for heating the liquid bath.

2. In a machine of the character described, a liquid bath, a set of drying rolls, 115 a sheet carrier for conveying the sheets from the bath to the drying rolls and means for heating the liquid bath and drying rolls.

3. In a machine of the character described, a liquid bath, a set of feeding rolls, 120 a set of drying rolls, a sheet carrier for conveying the sheets from the feeding rolls to the drying rolls, and means for heating the liquid bath.

4. In a machine of the character described, a liquid bath, a set of feeding rolls, 125 a set of drying rolls, a sheet carrier for conveying the sheets from the feeding rolls to the drying rolls and means for heating the liquid bath and the drying rolls.

5. In a machine of the character described, a liquid bath, a set of drying rolls, and an endless tape carrier having its receiving end immersed in the bath and its delivery end in proximity to the drying rolls for conveying the sheets from the bath to the drying rolls. 75
6. In a machine of the character described, a liquid bath, a set of drying rolls, an endless tape carrier for conveying the sheets from the bath to the drying rolls, a suitable receptacle, and a delivery roll arranged to receive the sheets from the drying rolls and deposit them in the said receptacle. 10
15. 7. In a machine of the character described, a liquid bath, a set of drying rolls, an endless tape carrier for conveying the sheets from the bath to the drying rolls, a delivery roll, arranged to receive the sheets from the drying rolls and a common means for driving the endless carrier, the drying rolls and the delivery roll. 80
20. 8. In a machine of the character described, a liquid bath, a set of feeding rolls, a set of drying rolls, an endless tape carrier for conveying the sheets from the feeding rolls to the drying rolls, a delivery roll arranged to receive the sheets from the drying rolls and a common means for driving the feeding rolls, the drying rolls, the endless carrier and the delivery roll. 90
25. 9. In a machine of the character described, a main frame, a supplemental frame, a pan having a trough at its forward end for containing a liquid bath, a pair of drying rolls mounted in the supplemental frame and a rearwardly and upwardly directed endless tape carrier arranged to convey the sheets from the liquid bath to the drying rolls. 95
30. 10. In a machine of the character described, a main frame, a supplemental frame, a pan having a trough at its forward end for containing a liquid bath, a pair of drying rolls mounted in the pan, a pair of feeding rolls mounted in the pan, a pair of drying rolls mounted in the supplemental frame and an endless tape carrier for conveying the sheets from the liquid bath to the drying rolls. 100
35. 11. In a machine of the character described, a main frame, a supplemental frame, a pan having a trough at its forward end for containing a liquid bath, feeding rolls mounted in the pan at the liquid bath, drying rolls and a delivery roll mounted in the supplemental frame and an endless tape carrier having the shaft at its receiving end mounted in the pan at the liquid bath and the shaft at its delivery end mounted in the supplemental frame adjacent to the drying rolls. 105
40. 12. In a machine of the character described, a main frame, a supplemental frame, a pan having a trough at its forward end for containing a liquid bath, feeding rolls mounted in the pan at the liquid bath, 110
45. 13. In a machine of the character described, a main frame, a pan mounted thereon having a trough at its forward end for containing a liquid bath, a supplemental frame mounted at the rear end of said pan, drying rolls mounted in said supplemental frame and an endless tape carrier for conveying the sheets from the liquid bath to the drying rolls. 115
50. 14. In a machine of the character described, a liquid bath, a pair of coacting drying rolls having blotting sheets wrapped around the same and free to extend and contract in a circumferential direction and a sheet carrier arranged to convey the sheets being treated from the bath to the drying rolls between said blotting sheets. 120
55. 15. In a machine of the character described, a liquid bath, a pair of coacting drying rolls having blotting sheets wrapped around the same and free to extend and contract in a circumferential direction, a sheet carrier arranged to convey the sheets being treated from the bath to the drying rolls between said blotting sheets, and means for heating said bath. 125
60. 16. In a machine of the character described, a liquid bath, a pair of coacting drying rolls having blotting sheets wrapped around the same and free to extend and contract in a circumferential direction, a sheet carrier arranged to convey the sheets being treated from the bath to the drying rolls between said blotting sheets, and means for heating said drying rolls. 130
65. 17. In a machine of the character described, a liquid bath, a pair of coacting drying rolls having blotting sheets wrapped around the same and free to extend and contract in a circumferential direction, a sheet carrier arranged to convey the sheets being treated from the bath to the drying rolls between said blotting sheets, and means for heating said bath and said drying rolls. 135
70. 18. In a machine of the character described, a liquid bath, a pair of drying rolls having blotting sheets wrapped around the same with their tail ends free and a sheet carrier arranged to convey the sheets being treated from the liquid bath to the drying rolls between said blotting sheets. 140
75. 19. In a machine of the character described, a liquid bath, a pair of drying rolls having blotting sheets wrapped around the same with their tail ends free, a sheet carrier arranged to convey the sheets being treated 145

from the liquid bath to the drying rolls between said blotting sheets, and fenders for the free ends of said blotting sheets upon opposite sides of the delivery end of the sheet carrier.

20. In a machine of the character described, a drying roll having a blotting sheet wrapped around the same, said blotting sheet being free to extend and contract 10 in a circumferential direction.

21. In a machine of the character described, a pair of drying rolls having oppositely arranged blotting sheets wrapped around the same, said blotting sheets being 15 free to extend and contract in a circumferential direction.

22. In a machine of the character described, a drying roll having a blotting sheet wrapped around the same with its tail end free.

23. In a machine of the character described, a pair of drying rolls having oppositely arranged blotting sheets wrapped around the same with their tail ends free.

In testimony, that I claim the foregoing 25 as my invention, I have signed my name in presence of two witnesses, this twenty-third day of November, 1911.

CHARLES L. CRABB.
